FIGURE 1 is a front elevational view of a bonnet showing my new design;

FIGURE 2 is a rear elevational view thereof;

FIGURE 3 is a side elevational view thereof; and

FIGURE 4 is another side elevational view thereof as it appears with the streamers tied together.

This design is characterized by a conical bonnet portion having a ruffled brim extending about the lower periphery thereof and a shaped head band under the ruffled brim extending around the periphery of the bonnet portion, said head band merging smoothly and integrally at the rear of the bonnet portion into generally triangular streamers substantially as shown.

I claim:

The ornamental design for a bonnet, substantially as shown and described.
